CAN BODY MAKER INTERCHANGEABLE FOR LONG AND SHORT STROKES

Roland E. Renard, Los Gatos, Calif., assignor, by mesne assignments, to National Can Corporation, Chicago, Ill., a corporation of Delaware

Filed May 3, 1954, Ser. No. 427,244

19 Claims. (Cl. 113—11)

This invention relates to a new and improved can body-maker.

A modern can body-maker is a machine having a series of longitudinally spaced work and idle stations and feed mechanism to advance body blanks from station to station. Body blanks are fed into a laterally offset hopper at the front of the machine, withdrawn from the hopper one at a time, and advanced transversely to the center of the machine. Upon reaching the center of the machine, the blanks are then fed longitudinally from station to station. The principal stations of the machine comprise the following:

Cross feed station 1 at which the blanks are fed from the hopper transversely to the center of the machine.

Idle station 2 to provide room for the adjacent work station.

Notching station 3 at which the corners of one longitudinal edge of the blank are notched to eliminate unnecessary overlapping when the blank is formed in a cylinder and the other longitudinal edge is slit adjacent the corners to facilitate subsequent bending of the edges.

Idle station 4 similar to station 2.

Edging station 5 at which the longitudinal edges of the blank are bent backwardly in hooks. In the instant machine the edging operation is performed at a single station, whereas in other body-makers the edging is many times performed at two stations.

Idle station 6 similar to stations 2 and 4.

Forming station 7 where the blank is formed into a cylinder, the hooked longitudinal edges being interlocked and the seam secured by hammering.

No detailed description of the forming station or of the soldering mechanism which is behind the forming station, is set forth herein since these portions of the machine form no part of the present invention, and the construction of conventional forming stations and soldering mechanisms is well understood by those skilled in the can-making art.

The advance of the can-body blank from station to station longitudinally of the machine is accomplished by a pair of feed bars which reciprocate longitudinally on opposite sides of the center. The feed bars carry opposed feed fingers, corresponding to the number of stations, which, on the feed stroke of the machine, engage the body blank and move it forwardly one station.

The reciprocating feed bars which carry the feed fingers and which determine the length of movement of the body blanks per cycle of the machine are driven from a crank which revolves in a horizontal plane. The throw of the crank determines the length of stroke of the feed bars. In conventional body-makers, the stroke of the feed bars is permanently fixed. Nevertheless, in commercial can making it is desirable, because of the cost of the body-maker, the amount of floor space which it occupies in a factory, and for various other reasons, to change over a given machine to work on body blanks of different lengths so as to manufacture cans of different heights. Thus, in

2

common can making practice, relatively tall cans having a maximum height of 5 inches and relatively short cans having a maximum height of 4 inches are sometimes produced on the same machine, but this practice is undesirable in that the speed of the machine for short cans is unnecessarily limited. On the other hand, in other instances two different machines are employed, one for cans of approximately 4 inches and another for cans of approximately 5 inch heights. This practice is undesirable in that the versatility of the machine is limited, thereby unduly increasing the required capital investment of the manufacturer.

One of the most important features of the present invention is the fact that the same machine may be used with a minimum amount of change-over, for two different lengths of stroke of the feed bars. By changing the throw of the crank which drives the feed bars and making certain other adjustments which are hereinafter described, the same machine may be converted from long stroke (e.g. 5½ inches) to short stroke (e.g. 4½ inches).

One of the most important means of accomplishing the stroke change-over is a reduction in the overall length of the work stations in the short stroke position by moving station 1 and station 3 closer to station 7, while at the same time substituting shorter feed bars.

A valuable advantage of employing an interchangeable length of stroke of the feed bars resides in the fact that the speed of production of cans of shorter height is considerably increased over the speed of production of taller cans. One of the reasons that special machines are employed for short cans is the fact that because of their shorter stroke and lighter weight of reciprocating parts, they can be driven at higher speed. In the present machine, substantially the same saving in weight and length of stroke is achieved on the shorter stroke as if a separate machine were employed.

Accordingly, the present invention provides a machine which may be operated on taller cans at one speed and on shorter cans at a higher speed. The changeover is accomplished with a minimum of labor and time and a minimum of necessary change parts.

One of the features of the machine hereinafter described is the fact that the cross feed station 1 which moves the can blanks from the vertical stack of blanks to the center of the machine is mounted on a separate sub-frame which is movable to two positions depending on the length of stroke. The drive of the mechanism mounted in the cross-feed sub-frame is self-contained and driven from the remainder of the machine through a chain. When the cross-feed is moved from the long stroke position to the short stroke position, the only important change in the cross-feed drive is substitution of a longer chain.

Still another feature of the invention is the mounting of the station 3 notching mechanism on a separate frame insert which, in side elevation, resembles an L. To change over from long to short stroke the right-hand and the left-hand notching station frame inserts are interchanged so that the horizontal legs of the L project in different directions for the different lengths of stroke. In the long stroke position the horizontal leg of the L of the insert projects rearwardly—i.e. toward the edger station. In the short stroke adjustment of the machine, the horizontal leg of the L-shaped notching frame insert extends toward and is partially overlapped by the cross-feed frame. Accordingly, the reversal of the right- and left-hand notching frame inserts and mechanisms to accommodate different strokes of the machine accomplishes a considerable saving in the cost of change parts and increases the convenience of change-over from one stroke to the other.

A further feature of the invention resides in the construction of the parts of the edger station. In many conventional body-makers, edging of the blank is accomplished at two different stations. In such body-makers the first edging operation involves a vertical movement of an edging steel which bends the marginal edge of the blank at approximately a right angle to the blank. At the second edging station of such prior constructed body-makers, the edge of the blank is bent backward so that it assumes an acute angle with respect to the blank. The employment of a two-stage edger increases the number and complexity of the working parts and, more importantly, increases the necessary length and weight of the feed bars, a principal limitation on the maximum speed of the machine.

In some prior constructed body-makers, edging is performed at a single station by means of a complex mechanical movement which moves an edging "steel" first vertically and then inwardly relative to the blank. Such single station edging mechanisms have required use of reciprocating parts and complex, slow-speed movements which have limited the maximum speed of operation of edging and the capacity of the machine. The present invention employs a single edging station but employs at the single station two edging steels which operate in sequence, one bending the edge of the blank approximately at right angles and the other bending the edge back at an acute angle with respect to the blank. The two steels are driven by eccentrics at a higher rate of speed than if a cam shaft were employed.

Other objects of the present invention will become apparent upon reading the following specification and referring to the accompanying drawings in which similar characters of reference represent corresponding parts in each of the several views.

In the drawings:

Fig. 1 is a side elevation, partially broken away in section, of the body-maker in long stroke position.

Fig. 2 is a view similar to Fig. 1 with the body-maker in short stroke position.

Fig. 3 is a top plan of the right-hand side of the machine in long stroke position.

Frame members and principal drives (Figs. 4, 10-12)

The machine incorporating the present invention is exceedingly complex and consists of various sub-assemblies, many of which are conventional in the can making art. Accordingly, many of the parts of the machine

have been eliminated or described only very briefly. The main frame 21 of the machine, only the upper part of which is shown in the accompanying drawings, supports the sub-frames and mechanism. Extending centrally longitudinal of the main frame is a drive housing 24 on which rests main table 22 which extends transversely. The side tables 23 fit on top of the sides of the main table 22.

In the center of the machine extending longitudinally thereof above the elevation of main table is a center table 26 which rests on main frame 21. Above center table 26 and pivoted to the front end thereof by pivot 25 is pressure bar spine 30 which may be lifted to provide access to other parts of the machine for adjustment and repair. The spine 30 supports other elements of the feed mechanism as hereinafter set forth.

On each side of the machine longitudinally extending side table 23 supports a longitudinal, horizontal side shaft 27. Side tables 23 have vertical side rails 28 which extend rearwardly behind the notching station to the forming station and are located inwardly and above shaft 27. The notching frame insert 29, hereinafter described in greater detail, fits in front of and is associated with and constitutes an extension of the side table 23, the side rails 31 and 28 of the notcher and edger being complementary.

In front of the notcher insert 29 is the cross-feed table 32 on a cross-feed sub-frame 33, which in the present body-maker is movable from a long-stroke position to a short stroke position depending upon the height of the can being manufactured. The cross-feed frame 33 and mechanism are likewise described in considerable detail.

Inserts 34 and 36 on either side of the machine fill in the space between the cross-feed sub-frame 33 and notcher insert 29 and side table 23, respectively; these inserts being change parts for the long stroke position.

The inner surfaces of the vertical rails of the cross-feed table 32, notcher insert 29, side tables 23, and inserts 34 and 36 are formed with coplanar laterally offset horizontal tracks comprising a continuous, horizontal feed table 39 along which the edges of the blank move as it is advanced from station to station.

The cross-feed mechanism is driven by means of a cross-feed shaft 41 which extends transversely of the machine, is journaled in bearings 42 in sub-frame 33 and is driven by chain 43 and sprockets 44 and 46 from cross shaft 47. Cross shaft 47 also drives side shafts 27 by means of meshing bevel gears 48 and 49 on either side of the machine and, by means of helical gears 51 and 52, cross shaft 47 is driven by vertical feed bar crank shaft 53.

The feed bars 56 are driven from the feed bar crank shaft 53. At the upper end of the crank shaft 53 is a crank cheek 57 having an eccentric crank pin 58. For different strokes of the machine, cheek 57 is interchanged for pins of different eccentricity. Crank pin 58 is connected to the front end of connecting rod 59 which extends rearwardly of the machine and is connected by means of wrist pin 61 to cross head 62 which reciprocates longitudinally horizontally of the machine in ways 63 formed in the inner vertical edges of a central longitudinal groove in main table 22. Cross head 62 carries transverse cross head drive bar 64 which fits in fitting 66 on top of cross head 62. On either side of the machine is a longitudinally horizontally reciprocating feed bar 56, the lower edge whereof at approximately midway of its length is formed with a notch 67 to receive the upper edge of the cross head drive bar 64. The outer edges of the feed bars 56 fit into longitudinally, horizontally extending ways 68 formed as grooves in the inner vertical faces of the rails of the cross-feed table 31, notcher frame insert 29, side tables 23 and inserts 34 and 36 and are held therein by retaining plates 69 which are connected to the various rails by screws 71.

Each feed bar carries a plurality of equi-distant feed fingers 72 corresponding in number to the number of

stations of the machine. Each finger is pivotally connected to the feed bar 56 by means of horizontal rivet 73 and is biased upwardly by means of a helical spring 74 rearwardly of the rivet 73. The upper edge 76 of the feed fingers, when spring 74 is expanded, projects up in the position shown in Fig. 11 and engages the trailing edge of the body blank and moves it rearwardly to the next station on the feed stroke. As the feed bars 56 retract, the feed fingers are depressed by reason of the leading edge of the blank contracting the slanting upper cam surface 77 of the feed fingers, springs 74 being compressed. The distance between feed fingers 72 is equal to the distance between stations of the machine and thus as the stroke of the body-maker is changed from a long stroke to a short stroke, the length of the feed bars 56 and the distance between feed fingers 72 is correspondingly changed. As has been stated, the weight of the reciprocating feed bars 56 is one of the limitations upon the speed of the machine and hence shortening of the bars on the short stroke is highly desirable.

Pressure bar spine 30 has a plurality of laterally projecting ears 81 which are connected to longitudinally extending skid supports 82. Below supports 82 are short, horizontal, longitudinal pressure bar skids 83 at stations 2, to 6, each presser bar skid being a short longitudinal, horizontal foot having vertical pins 84 biased downward by spring 86 from supports 82 so as to create a drag restraining any tendency of the moving blank to slide by inertia beyond its proper station.

To prevent retraction of the blanks as the feed bars retract, stationary dogs 87 are mounted on the center bar 78 behind idle station 2 for both its long stroke and short stroke position to engage the center of the trailing edge of the blank and prevent its retraction. Dogs 87 are biased downwardly by springs 88 and during the feed movement of the feed bars the blanks moving from station 1 to station 2 contact the lower slanted cam surfaces 89 of the dogs and pivot them upwardly around pivot 91 so as to permit movement of the blanks.

The foregoing described mechanism generally sets forth the various portions of the machine which are common to all or several of the stations. The individual stations are now hereinafter described in such detail as is necessary to enable one skilled in the can-making art to understand the operation thereof, it being understood that by reason of the fact that many of the mechanisms and stations are conventional, detailed description thereof has been eliminated.

Station 1—cross feed station (Figs. 3-5)

Cross feed station 1 mechanism is driven by cross feed shaft 41 which is in turn driven from cross shaft 47 by sprockets 44 and 46 and chain 43. Shaft 41 on its inner end carries a crank cheek 96 bearing a crank pin 97 which is connected to the lower end of connecting rod 98, the opposite end of which is connected by wrist pin 99 to sucker cup slide 101 which reciprocates vertically in ways in a housing 102 connected to the cross feed sub-frame 34. The upper end of the sucker cup slide 101 carries a fitting 103 which in turn bears on its top face a pair of sucker cups 104. The fitting 103 and housing 102 are cored out to provide a passageway 105 which is connected to a vacuum pump (not shown) so that at the upper stroke of the sucker cups 104 a vacuum is drawn thereon and at the lower part of the stroke the vacuum is broken. Above the feed table is a stack 106 of blanks 20(1) held in stack guards 107 which carry spring biased detents 108 engaging the edge of the lowermost blanks to prevent subsequent blanks from following the bottom-most blank as it is withdrawn. At the upper end of their stroke, the vacuum cups 104 engage the bottom surface of the lowermost blank and draw a vacuum thereupon. As the shaft 41 revolves and the cups are lowered, the lowermost blank is flexed and escapes from the detents 108 and is withdrawn to the

level of the cross feed table 32 whereupon the vacuum is broken.

Shaft 41 also drives vertical feed drive shaft 111 by means of mating bevel gears 112 and 113, shaft 111 being suitably journaled in the cross feed sub-frame in bearings 114. Feed crank cheek 116 on the upper end of vertical cross-feed drive shaft 111 carries a crank pin 117 which is connected by link 118 to feed cross head 119 which slides horizontally transversely of the machine in ways 121 formed in the cross feed table 32. After the blank is deposited on the feed table 32, cross feed finger 122 which is connected to cross feed cross head 119 picks up the blank and moves it inwardly transversely of the machine. Side guides 124 maintain the blank in proper alignment. It will be understood that a grain breaking flexing roll assembly 123 is installed between the feed stack 106 and the center of the machine to break the grain of the blank to facilitate subsequent forming. The construction of grain-breaking flexing roll assembly 123 is well understood in this art and hence description thereof is unnecessary to an understanding of the present invention.

After leaving the rolls 123, the blank 20(1) is guided by transfer plate 126 between top plate 127 and bottom plate 128 attached to the underside of pressure bar spine 30 and to top of center table 26, respectively, opposite station 1.

Idle station 2

No work is performed upon the blank 20 at any of 30 the idle stations 2, 4 or 6. At station 2 the feed bars 56 as they reciprocate advance the blank 20(2), which has been fed transversely on the cross feed to a position in front of the rearmost feed fingers 72(1), forwardly one station by pushing the trailing edge of the blank. At 35 idle station 2, the presser skids 83 engage the top surface of the blank biasing the lower surface against the feed table 39 and bring it to a stop. Dog 87 engages the trailing edge of the blank to prevent its retraction. As the feed bar retracts the leading edge of the blank engages the slanted cam surface 77 of the feed fingers 72(2) causing the feed finger to be depressed against the action of spring 74.

Essentially the same structure is located at stations 4 and 6.

Notching station (Figs. 6, 13)

Station 3 notches the corners of one longitudinal edge of the blank 20(3) and slits the other longitudinal edge inwardly of the corners in a manner well understood in 50 the can-making art. For such purpose a die block 131 is mounted on the notcher frame insert 29 below the feed table 39 and a die 132 complementary in shape to the die block is mounted above the level of the feed table 39. The die 132 is caused to reciprocate vertically and by 55 co-action with the die block 131 performs the notcher operations. The construction of the die and die block is complicated but well understood in this art and since no novelty resides in the exact construction thereof a detailed description is not set forth in this specification.

The notcher frame insert 29 is, as has been indicated, of a generally L-shape in side elevation, the horizontal extension 133 of the L providing a spacer which is important in changing over the machine from the short stroke to the long stroke. In the long stroke position shown in Fig. 1, the notcher frame insert 29 is positioned with the horizontal extension 133 directed rearwardly toward the edger station 5 thereby locating the notcher station 3 farther from the edger to accommodate the longer stroke of movement. In this position, the screws 60 134 which attach the frame insert to the main table engage holes 136. In the short stroke position, the left-hand and right-hand notcher frame inserts 29 are reversed whereupon the extension 133 is directed forwardly of the machine and the frame insert is held to the main table by screws 134 which fit in holes 137.

The frame insert 29 contains a dove-tail slideway 138 extending vertically and in the slideway fits slide 139 to which is fastened die holder 135 by means of screws 140. Dies 132 are fastened in holder 135 by screws 141 so that the die is reciprocated as the slide 139 reciprocates in way 138. Reciprocation of the slide is accomplished by means of eccentric 142 on side shaft 27, the eccentric being engaged by eccentric strap 143 and cap 144 which are connected to connecting rod 146, the upper end of which is attached to slide 139 by wrist pin 147 which passes through aligned apertures in the connecting rod 146 and bosses 148 extending outwardly on the slide 139.

Thus, blank 20(3) is moved to the notcher station, centered by the inner edge of stationary block 145 which is an upward extension of die block holder 150 to which die block 131 is fastened and comes to rest by reason of the resistance of skids 83, die 132 moves vertically downwardly notching the edges of the blank in proper position, the scrap pieces of tin plate falling down through passageways 149. The die 132 then moves upwardly and the blank is fed from the notcher station to idle station 4 by feed fingers 72(3) in the same manner as previously indicated with respect to the feed of the blank from the cross-feed transfer to idle station 2.

It will be understood that on the short stroke of the machine the eccentric 142 is located on side shaft 27 to the right (Fig. 2).

The change-over from the short stroke to the long stroke by reversal of the left- and right-hand notcher frame inserts 29 is facilitated by the construction of the sub-frame. The center line of the slide on the long stroke is indicated by reference numeral 151 and the center line of the slide on short stroke is indicated by reference numeral 152. Lines 151 and 152 are equidistant from, but on opposite sides of, center line 153 of the insert. Center line 153 is constant for both positions of the insert.

It will be understood that the dies 132 and die blocks 131 are interchanged for corresponding elements for different lengths of blanks so that the notches will be located in proper position.

Edger station (Figs. 7-9)

After the blank 20(5) has been moved by feed fingers 72(4) to the edger station, the blank is clamped against feed table 39 on the side table 23 by a longitudinally extending clamp bar 156 on each side of the machine. The outer edge of the clamp bar is formed in a wedge with its upper edge 157 directed inwardly in an acute angle to coact with the second operation edger steel to bend the edge of the blank at the same angle in a manner hereinafter set forth. Clamp bars 156 are actuated in a short arcuate travel by yoke 158 which is pivotally mounted on pivot shaft 159 journaled in bosses 161 on side table 23. A vertically movable adjustment screw 162 threaded into longitudinal connecting portion 163 of yoke 158 contacts the upper end of cam rod 164, the lower end of which is provided with a cam follower roller 166 which engages cam 167 on side shaft 27. Cam rod 164 has an enlarged guide 168 which is received within a bore in bracket 169 which is attached to side table 23. Spring 171 is interposed between the guide 168 and a cap 172 threaded into bracket 169 to keep follower 166 in contact with cam 167. Timing of cam 167 is such that during the cycle when the blank is feeding from station to station the clamp bar 156 is raised in the position shown in Fig. 7 of the accompanying drawings. When the blank has come to rest, cam rod 164 is lifted which causes the yoke 158 to rock about pivot shaft 159 until the clamp assumes the position shown in Figs. 8 and 9, whereupon it clamps the blank between clamp bar 156 and feed table 39.

At the edger station are first operation and second operation edger steels 173 and 174, respectively, extend-

ing longitudinally. There is a set of steels on each side of the machine. The first operation steel 173 is held in a rocker arm 176 which is pivoted on pivot shaft 159 and the end of the rocker arm opposite first steel 173 is provided with a boss 177 through which fits wrist pin 178 which also passes through the bifurcated end 179 of a fitting 181 on the upper end of connecting rod 182. The lower end of the connecting rod 182 is formed with an eccentric strap 183 and cap 184 which engage the eccentric 186 on side shaft 27. As side shaft 27 revolves, rocker arm 176 rocks around the pivot shaft 159 causing a cycle of movement of the first operation steel as hereinafter described.

Second operation steel 174 is likewise engaged by second rocker arm 187 which is pivotally mounted on pivot shaft 159, the opposite end of which is formed with a boss 188 through which fits wrist pin 189 which also passes through the bifurcated upper end 191 of second connecting rod 192, the lower end of which is provided with an eccentric strap 193 and cap 194 which pass around second eccentric 196 on side shaft 27. As side shaft 27 revolves, second steel 174 is rocked through a cycle of operations hereinafter described in detail.

First operation steel 173 comprises three parts, an uppermost curved flank 201 which has its center of curvature on the axis of pivot shaft 159, a transverse shoulder 202 and a lower flank 203. During the feed cycle of the machine the first steel is approximately in the position shown in Fig. 7 whereby the upper flank 201 is at the level of the feed table 39 so that the outer edge of the blank 20(5) contacts the flank and is thus centered relative to the machine. After the clamp bar 156 has clamped the blank against the side table as shown in Fig. 8, the cycle of the first steel brings the shoulder 202 upward so that it engages the bottom surface of the edge of the blank 20(5) and bends it upwardly against the outer edge of the clamp bar 156. One feature of the present machine is that the axis of the right-hand pivot shaft 159, as shown in the accompanying Figs. 7 to 9, is located above the feed table 39. Hence, pivotal movement of the shoulder 202 produces a glancing, upward, inward movement rather than a straight vertical movement and the bending of the blank 20(5) is less likely to cause rupture than in ordinary edger mechanisms.

After the first steel 173 has risen to the position shown in Fig. 8 it begins to retract until it reaches the position shown in Fig. 9 at the bottom of its cycle and is out of the way to permit the second operation steel 174 to come into operative position.

The lower edge 204 of second operation steel 174 has a slanted surface which is complementary to the surface 157 of clamp bar 156, the angle being the desired ultimate angle of the bent-back edge of the blank 20(5) relative to the main body of the blank. The second operation steel moves 174 down to the position shown in Fig. 9 and bends the edge of blank 20(5) back against the clamp bar 156 to the position shown.

After the sequence of operation shown in Fig. 8 has been completed, the second operation steel 174 moves upward until it eventually reaches the position shown in Fig. 7 and the clamp 156 moves upward to the position shown in Fig. 7. Upon release of the blank 20(5) from between the clamp bar and feed table, the blank is free to move longitudinally of the machine to idle station 6.

The steels 173 and 174 shown in Figs. 6 to 8, inclusive, are on the right-hand side of the machine as viewed from the front. On the right-hand side, the edge of the blank is bent upwardly and inwardly. On the left-hand side of the machine, however, the edge of the blank is bent downwardly and inwardly. Accordingly, on the left-hand side of the machine (not shown) the pivot shaft 159 is below the level of the feed table 39; first and second operation steels 173 and 174 are inverted from the position shown in Figs. 7 to 9 and the edge of the feed

table 39 is formed wedge-shaped resembling the lower edge 157 of the clamp bar 156. The construction of the left-hand side of the edger station will be apparent to one skilled in the can-making art from a consideration of the description and illustration of the right-hand side of the machine which has been set forth.

Change-over from long stroke to short stroke

With the exception of Figs. 2 and 4, the accompanying drawings are shown with the machine in long stroke position. In such position the feed fingers 72 are spaced apart a distance equal to the long stroke (e.g. 5½ inches between centers) and the throw of crank 57, is, accordingly, one-half that distance. The cross feed table 32 and cross feed sub-frame 33 are to the left as viewed in Fig. 1. In order to drive shaft 41, the shorter chain 43 is employed to connect sprocket 44 to sprocket 46. The notcher insert blocks 29 are so positioned that the horizontal extension 133 is directed rearwardly of the machine.

In order to change over the machine to the shorter stroke, shorter feed bars 56 are substituted, the distance between the feed fingers 72 equaling the shorter stroke (e.g. 4½ inches). A shorter throw crank 57 is substituted to accommodate the shorter stroke of the feed bars. Cross feed sub-frame 33 is moved to the right. A longer chain 43 is employed to connect sprocket 44 to sprocket 46.

The notcher frame inserts 29 are reversed from the right-hand to the left-hand side of the machine, and vice-versa, so that the extensions 133 are directed forwardly of the machine. Eccentric 142 is moved to the right so as to line up with connecting rod 146.

It will further be understood that the notcher die 132 and die block 131 are interchanged for shorter dies and blocks by reason of the shorter blanks accommodated and that the edger steels 173 and 174 and clamp bars 156 are likewise interchanged for shorter corresponding members to accommodate shorter blanks. Shorter pressure bar skids 83 are likewise employed.

Change-over for different diameter cans

The width of the bank 20 depends upon the diameter of the can to be formed. Change over for diameter changes in the present machine does not differ materially from change-overs in conventional body-makers and the details thereof are not described herein.

Operation

The operation of the machine is essentially the same whether the long stroke or short stroke is employed. Blanks 20 are deposited in the stack 106 above the cross feed table 32. As the shaft 47 is driven by an electric motor (not shown) crank 96 revolves which causes vertical reciprocation of the suction cups 104. With each cycle of the machine the lowermost blank 20(1) is drawn out of the stack to the level of the cross feed table. In timed relationship to the withdrawal of the blank, upon rotation of crank 118, cross feed finger 122 drives the blank inwardly onto the center of the machine between plates 127 and 128 at the level of the feed table 39.

At the time the blank is fed between plates 127 and 128 the feed bars 56 are in retracted position by reason of the position of crank 57. As crank 57 revolves, the feed bars are moved rearwardly, feed fingers 72(1) engaging the trailing end of the blank 20(1) and pushing it rearward to idle station 2. At idle station 2 the blank 20(2) is brought to rest by the drag created by skids 83 and the dog 87 engages the trailing edge of the blank and prevents its retraction.

On the next stroke of the machine, the feed fingers 72(2) move the blank to notcher station 3. The rotation of shaft 47 likewise drives side shaft 27 and this in turn rotates eccentric 142 and causes notcher slide 139 to reciprocate. Downward movement of the slide and die 132

75

carried on the slide notches out the edge of the blank 20(3) on one side and forms corresponding slits on the edge on the other side. The slides 139 move upward in time for the next feed cycle whereupon fingers 72(3) move the blank 20(4) to idle station 4.

On the next feed cycle, feed fingers 72(4) move the blank to the edger station 5. At the edger station, the blank 20(5) is centered by flanks 201 of first operation steel 73. Clamp 156 then is depressed by rotation of the side shaft 27 which causes cam 167 to raise cam follower 166, rocking yoke 158 about pivot shaft 159. First edger steel 173 on the right-hand side moves upward, causing shoulder 202 to engage the undersurface of the edge of the blank 20(5) and move it upwardly and inwardly at a glancing angle which is occasioned by the fact that the axis of pivot shaft 159 is above the level of feed table 39. On the left-hand side of the machine the axis of pivot shaft 159 is below the feed table so that the first operation steel (which is inverted with respect to the right-hand side of the machine) moves downwardly and inwardly in a glancing stroke. On the right-hand side, the first breaker steel 173 then retracts as the second operation edger steel 174 moves downwardly and the lower beveled edge 204 of the second steel engages the blank and bends it inwardly in cooperation with the slanted surface 157 of the clamp bar 156 until the proper angle is attained. On the left-hand side of the machine the second edger steel moves upwardly on its working stroke rather than downwardly. At the end of the cycle the second steels 174 retract and the clamp 156 moves upwardly permitting feed fingers 72(5) to move the blank 20(6) rearwardly on the next feed stroke of the machine.

Feed fingers 92(5) move the blank 20(6) to idle station 6.

On the next stroke of the machine, feed fingers 72(6) move the blank rearward to the forming station 7 which is not described here in detail. The cylinder 20(7) thus formed is then soldered by soldering mechanism (also not shown).

What is claimed is:

1. In a variable stroke can body-maker machine for manufacturing can bodies from flat blanks:
  - a main frame;
  - a plurality of work stations spaced longitudinally on said frame comprising a transfer station, a notcher station, an edger station and a forming station, the location of a plurality of said stations being changeable for a long stroke position and a short stroke position;
  - reciprocatory feed means for advancing blanks from station to station intermittently;
  - and feed drive means for said feed means;
  - said feed means and feed drive means being interchangeable for long stroke and short stroke;
  - said transfer station comprising a transfer sub-frame;
  - said transfer sub-frame being movable longitudinally of said main frame from a long stroke to a short stroke position;
  - transmission means for driving said transfer station adjustable for different positions of said transfer sub-frame;
  - said notcher station comprising a notcher sub-frame on each side of the machine, a slide reciprocable on each said notcher subframe, a die on each said slide, a cooperating die block on each said notcher sub-frame, and notcher drive means for reciprocating said slides;
  - said notcher sub-frame being movable on said main frame from a long stroke to a short stroke position.
2. A machine according to claim 1 in which are provided side shafts on either side of the machine journaled in said side frames, said notcher drive means and edger station means being driven from said side shafts, said feed drive means, transfer station means and side shafts being driven synchronously.
3. A machine according to claim 2 in which said side shafts are permanently positioned and there are means

carried on said side shafts for actuating said notcher drive means both in long stroke and short stroke position.

4. A machine according to claim 1 in which said notcher sub-frames are L-shaped in elevation, the horizontal extensions of said notcher sub-frames extending in the same direction, said notcher sub-frames being interchangeable from one side of the machine to the other so that in long stroke position said extensions extend in one direction and in short stroke position said extensions extend in the opposite direction.

5. A machine according to claim 1 in which are provided idler stations between at least some work stations.

6. A machine according to claim 1 in which said feed means comprises longitudinal feed bars, a plurality of equally spaced feed fingers pivotally mounted on said bars to engage the trailing edge of a blank and means mounting said bars for reciprocation.

7. A machine according to claim 6 in which the distance between fingers is equal to the distance between stations and said feed bars are interchangeable for long stroke and short stroke positions of said work stations.

8. A variable stroke can body-maker machine for manufacturing can bodies from flat blanks comprising:

a main frame; transfer means mounted on said main frame for transferring blanks one at a time into the machine;

notcher means mounted on said main frame for notching the edges of a blank;

edger means mounted on said main frame for edging a blank;

and means for advancing a blank a uniform distance at a time to a plurality of stations, including stations at which said transfer means, notcher means and edger means are located;

said feed means, transfer means, notcher means and edger means being driven synchronously;

said feed means being interchangeable for a long stroke and a short stroke;

said transfer means being movable on said main frame from a long stroke position to a short stroke position, said notcher means being movable on said main frame from a corresponding long stroke position to a corresponding short stroke position.

9. A machine according to claim 8 in which said notcher means comprises a notcher frame insert on each side of the machine, each having a longitudinal extension projecting in one direction in long stroke position and in the opposite direction in short stroke position.

10. A machine according to claim 8 in which said notcher means comprises notcher frame inserts, one on each side of the machine, said inserts being interchangeable for different lengths of stroke.

11. A machine according to claim 8 in which said notcher means comprises notcher frame inserts, one on each side of the machine, said inserts being interchangeable on opposite sides of the machine for different lengths of stroke.

12. A machine according to claim 8 in which said transfer means, notcher means and edger means for long stroke position are spaced apart multiples of said long stroke and for short stroke position are spaced apart multiples of said short stroke and in which said notcher means comprises a notcher frame insert having a horizontal extension in one direction and having a reciprocating slide and a die mounted on said slide, the center line of said slide and die being offset to one side of the center line of said insert.

13. A machine according to claim 12 in which the center line of said insert is the same for long and short stroke positions and in which the center line of said slide

and die is spaced forwardly from the center line of said insert in long stroke position and spaced rearwardly an equal distance from said center line of said insert in short stroke position.

5. 14. A notching mechanism for a can bodymaker machine adjustable for a long stroke position and a short stroke position, comprising a main frame, a pair of notcher subframes on transversely opposite sides of said main frame movable on said main frame from a long stroke position to a short stroke position by interchange of said subframes to opposite sides of said main frame, means securing said subframes on said main frame in each of said positions, a slide on each said subframe reciprocable on said subframe, a die on each said slide, 15 a pair of die blocks on said subframe cooperable with said dies, drive means for reciprocating said slides, said subframes being L-shaped in elevation, the horizontal extensions of said subframes extending in the same longitudinal direction, said subframes being interchangeable from one side of the machine to the other so that in long stroke position said extensions extend in one direction and in short stroke position said extensions extend in the opposite direction.

20 15. A mechanism according to claim 14, in which in long stroke position said horizontal extensions extend toward the discharge end of the mechanism and in short stroke position said horizontal extensions extend away from the discharge end of the mechanism.

30 16. A mechanism according to claim 14, in which the longitudinal center line of said slide is offset longitudinally to one side of the longitudinal center line of said subframe.

35 17. A mechanism according to claim 16, in which the longitudinal center line of said mechanism is the same for long and short stroke positions and in which the longitudinal center line of said slide is spaced toward the discharge end of said mechanism from the longitudinal center line of said mechanism in long stroke position and is spaced from said longitudinal center line of said mechanism an equal distance away from said discharge end in short stroke position.

40 18. A notching mechanism for a can bodymaker adjustable for a long stroke position and a short stroke position, comprising a notcher frame having an extended

45 length movable between a long stroke and a short stroke position and having a longitudinal frame center line, a slide reciprocable on said notcher frame and having a longitudinal slide center line, said slide center line being displaced longitudinally from said frame center line, and 50 cooperating notcher die means on said slide and frame.

19. A mechanism according to claim 18, in which said slide center line is spaced relative to said frame center line toward the discharge end of said mechanism in long stroke position and away from the discharge end of said 55 mechanism in short stroke position.
